UNITED STATES PATENT OFFICE.

HENRY K. SPENCER, OF WINCHESTER, MASSACHUSETTS, ASSIGNOR TO THE BLANCHARD MACHINE COMPANY, OF CAMBRIDGE, MASSACHUSETTS, A CORPORATION OF MASSACHUSETTS.

ABRASIVE WHEEL.

Application filed November 27, 1925. Serial No. 71,576.

This invention relates to a novel abrasive wheel embodying a series of blocks of abrasive material, and means to cause them to be held in place and to permit them to be adjusted from time to time to compensate for wear, as well as to permit them to be replaced by new ones, as occasion requires.

The invention will be best understood by reference to the following description, when taken in connection with the accompanying drawings of one specific embodiment thereof, while its scope will be more particularly pointed out in the appended claims.

In the drawings:

15 Fig. 1 is a bottom plan of an abrasive wheel exemplifying the invention;

Fig. 2 is a sectional view on an enlarged scale on line 2—2 of Fig. 1, looking in the direction of the arrows on said line:

20 Fig. 3 is a sectional view on line 3—3 of Fig. 2, looking in the direction of the arrows on said line;

Fig. 4 is a sectional view on line 4—4 of Fig. 2, looking in the direction of the arrows 25 on said line;

Fig. 5 is a sectional view on an enlarged scale on line 5—5 of Fig. 1, looking in the direction of the arrows on said line;

Fig. 6 is a sectional view similar to Fig. 5, 30 showing the abrasive block or segment in a different position, and with a stop at its upper end;

Fig. 7 is a sectional view on an enlarged scale on line 7—7 of Fig. 5, looking in the direction of the arrows on said line; and

Fig. 8 is a sectional view on a reduced scale on line 8—8 of Fig. 2, looking in the direction of the arrows on said line.

Referring to the drawings, and to the embodiment of the invention which is selected for exemplification, and having reference at first more particularly to Fig. 1, the wheel comprises a chuck body including a ring 11 and a disk 12, suitably secured to each other, as by cap screws 13 (see Fig. 2), extending loosely through the disk and threaded into the ring. The chuck presents a holder for a series of blocks or segments 14 of abrasive material, which, as shown in Fig. 1, are in spaced relationship with one another. Centrifugal force is utilized to exert pressure on the blocks to hold them in place. This is conveniently accomplished in the present example by making each block wedge-shaped, with the small end of the wedge outward, and

by providing the ring 11 with a similarly-shaped recess 15. In other words, each block has sides which converge in an outward direction from the axis of the wheel, and the recess has similarly converging sides, with which the sides of the block contact. Looking at it in another way, the ring may be said to present a series of wedges interposed between the blocks. The depth of the recess, of course, is such that the small end of the block does not bottom in the recess (see Fig. 3). In practice, it is found that a wedge-like block having an included angle of 22 degrees gives excellent results.

To supplement the clamping action so obtained, which might be insufficient by itself, and to hold the blocks securely when the wheel is not running, clamping means are provided, the same in the present example including clamping bolts 16, nuts 17, and yokes 18, each spanning two adjacent blocks, and mounted on a pivot 19 on its associated bolt, thereby to equalize the clamping pressure between the two blocks. It should here be mentioned that the weight of these yokes, bolts and nuts, is added to that of the blocks in utilizing centrifugal force to clamp the latter when the wheel is running. Each bolt has a loose fit in an opening 20 provided in the ring 11, and each nut is received in a chamber 21 presented by the ring. The nut presents a polygonal head 22 within the chamber for the attachment of a socket wrench. This arrangement is preferred, because it presents no projecting parts on the periphery of the wheel. In order that the bolt and its nut may be lubricated, and water excluded from their working surfaces, the nut in the present example presents a chamber 23 to receive a supply of grease, some of which, as the nut is screwed into place, squeezes out along the contacting surfaces of the bolt and nut. Herein, the bolt is provided with a longitudinal groove 24, extending from the end of the bolt to a point some distance beyond the nut, thereby to afford a passage for grease to work its way out along the bolt, and to enter the clearance space between the bolt and the opening 20, thereby to exclude from the working surfaces water which might otherwise enter and cause the working surfaces to rust.

In the present embodiment, the yoke does not contact with the two blocks which it clamps, but instead it rests against two shoes

25, which contact with the blocks, and these shoes are supported in such a manner that, while they are capable of moving toward and from the axis of the wheel a sufficient amount and of accommodating themselves to the inner faces of the blocks, they are incapable of moving lengthwise of the axis of the chuck body, as well as circumferentially. This is conveniently accomplished by mounting each shoe on a comparatively stiff spring 26 (see Figs. 5 and 7), which is secured to the chuck body, herein by a ring 27, which, as shown in Fig. 2, is secured to the ring 11 by cap screws 28 extending loosely through lugs 29 presented by the ring 11, said screws being threaded into the ring 27. Referring again to Figs. 5 and 7, each spring is suitably secured to the ring 27, as by rivets 30, and to the shoe 25, as by rivets 31. Herein, as shown in Fig. 5, the lower end of the spring extends into a groove 32, presented by the shoe. The spring, being inextensible, prevents movement of the shoe lengthwise of the chuck body axis, and being wide (see Fig. 3), prevents circumferential movement of the shoe. However, advantage is taken of the flexibility of the spring in other directions. For example, the spring bends under the outward thrust of the yoke, and not only allows the shoe to move outward, but also to align itself vertically with the face of the block. The spring is also capable of twisting, and thereby allowing the shoe to align itself horizontally with the face of the block. As a means to prevent the yoke and the bolt from rotating about the axis of the latter, the yoke and the shoes have suitable interengaging means, herein lugs 33 on the shoes, underlying the yoke and engaged by the latter.

40 Under most circumstances, the described clamping means is effective to prevent the blocks from being forced in an upward direction into the chuck body. Under some exceptional circumstances, it may be desirable to provide a positive stop to prevent the blocks from being forced up into the chuck body. If the blocks are of sufficient length, the positive stop may be presented by the disk 12 above the blocks, the disk in the present case being provided with an abutment 34 (see Fig. 5), which limits upward movement of the blocks. When finally the blocks have been worn away to a considerable extent, so as to require adjustment in a downward direction (see Fig. 6), upward displacement of the blocks may be prevented by the provision of studs 35 threaded into the ring 11, and presenting stops 36 overlying the upper ends of the blocks. Trapped holes 37 may be provided at various heights to receive the studs.

55 As a means to afford protection to the clamping devices, from the water supplied to the interior of the wheel during the grinding operation, there is provided in the present embodiment a guard comprising a ring 38

secured to and depending from the disk 12, like a skirt.

Having thus described one embodiment of the invention, but without limiting myself thereto, what I claim and desire by Letters 70 Patent to secure is:

1. In an abrasive wheel, the combination of a series of blocks of abrasive material, and a holder therefor comprising a series of yokes each spanning two blocks, and a series of 75 clamping bolts pivotally connected to said yokes, respectively, and arranged to permit said yokes to rock toward and from said blocks to cause them to exert clamping pressure on said blocks.

2. In an abrasive wheel, the combination of a series of blocks of abrasive material, and a holder therefor comprising a series of yokes each spanning two blocks, there being but one yoke to each two blocks, a series of radial 85 bolts and nuts to cause said yokes to clamp said blocks, there being but one bolt and one nut to each two blocks, said yokes being secured to said bolts and means engaging said yokes to prevent rotation of said yokes.

3. In an abrasive wheel, the combination of a series of blocks of abrasive material, a chuck body presenting abutments for said blocks, a series of shoes engaging said blocks, means supporting said shoes yieldingly in radial directions and unyieldingly in an axial direction, and means to urge said shoes toward said blocks and to urge said blocks toward said abutments.

4. In an abrasive wheel, the combination of a series of blocks of abrasive material, a chuck body presenting abutments for said blocks, a series of shoes engaging said blocks, springs supporting said shoes resiliently in radial directions and rigidly in an axial direction, and means to urge said shoes toward said blocks and to urge said blocks toward said abutments.

5. In an abrasive wheel, the combination of a series of blocks of abrasive material, a chuck body presenting abutments for said blocks, a series of shoes resiliently supported by said chuck body and engaging said blocks, a series of clamping yokes each engaging two of said shoes, and a series of clamping bolts to cause said yokes to urge said shoes toward said blocks and to urge said blocks toward said abutments.

6. In an abrasive wheel, the combination of a series of blocks of abrasive material, a chuck body presenting abutments for said blocks, a series of shoes resiliently supported by said chuck body and engaging said blocks, a series of clamping yokes each engaging two of said shoes, a series of clamping bolts and nuts to cause said yokes to urge said shoes toward said blocks and to urge said blocks toward said abutments, and means to prevent rotation of said yokes.

7. In an abrasive wheel, the combination of a series of blocks of abrasive material, a chuck

body presenting abutments for said blocks, a series of shoes flexibly supported by said chuck body and engaging said blocks, a series of clamping yokes each engaging two of said shoes, a series of clamping bolts and nuts to cause said yokes to urge said shoes toward said blocks and to urge said blocks toward said

abutments, and means presented by said shoes and said yokes to prevent rotation of said yokes. 10

In testimony whereof, I have signed my name to this specification.

HENRY K. SPENCER.
